INVENTOR

Robert S. Blair

UNITED STATES PATENT OFFICE

ROBERT S. BLAIR, OF STAMFORD, CONNECTICUT

CLAW HAMMER

Application filed February 4, 1925. Serial No. 6,754.

This invention relates to construction for claw hammers and the like.

One of the objects of the invention is to provide a device of the above nature having a nail extracting claw highly efficient in action. Another object is to provide such a device by means of which a nail may be extracted in its entirety in a convenient and dependable manner. Another object is to provide a device of the above nature which is strong and rugged, capable of dependable service, and which is yet simple and inexpensive. Other objects will be in part obvious or in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawing, in which are shown various possible embodiments of this invention,

Figure 1 is a side elevation of a hammer;

Figure 2 is a section substantially along the line 2—2 of Fig. 1, showing the claw portions of the hammer in plan;

Figures 3, 4 and 5 are sections taken along the lines 3—3, 4—4 and 5—5 respectively of Fig. 2;

Figures 6, 7, 8 and 9 are sections substantially similar to that of Fig. 4, being taken respectively through various modified forms of nail extracting claws;

Figure 10 is a view similar to Fig. 2 showing in plan a further modified form of claw;

Figure 11 is a side elevation of the construction shown in Fig. 10;

Figure 12 is similar to Fig. 11 showing the addition of another feature;

Figure 13 is a view similar to Figs. 2 and 10 showing a further modification, and

Figure 14 is a side elevation of the construction shown in Fig. 13.

Similar reference characters refer to similar parts throughout the several views of the drawing.

Referring now to Figure 1 of the drawing in detail, there is shown a hammer com-

prising a main body 10 in which is secured the handle 11, the body being provided with a hammer head 12, and opposite thereto with a nail extracting claw 13. As is seen in Figure 2, the body of the claw 13 joining the main body 10 of the hammer is a solid member from which project the outwardly and rearwardly curving jaws 14 and 15. These jaws are spaced from each other at their ends preferably to a distance a little greater than the diameter of a large-sized nail, the space between the jaws gradually narrowing until the jaws meet where they merge into the body 13 of the claw.

These jaws 14 and 15 are preferably made of a tough resilient steel, and suitably tempered. Their cross-section varies progressively from one end to the other, as is best brought out in Figures 3, 4 and 5. Referring to these figures, it is seen that the metal from which the jaws are made is relatively thin, and along the outer sides of the two jaws this metal is rolled over, as indicated at 14^a and 15^a. This leaves the inner portions 14^b and 15^b of the jaws, which portions engage the nail, resilient and springy, while the outer portions 14^a and 15^a of the jaws are substantially rigid and unyielding. In addition, the metal of the jaws is preferably somewhat thickened from the ends thereof toward the body portion 13, so that their strength is gradually built up as may be appreciated by a comparison of Figures 5, 4 and 3 in the order named. The inner nail engaging portions 14^b and 15^b of the two jaws forming the claw are at the end of the claw substantially flat, as brought out in Figure 5. As these portions approach the body 13, they are curved upwardly to a gradually increasing height, as brought out in Figures 4 and 3.

In the use of this claw, the extraction of the nail may be started by forcing the parts 14^b or 15^b at the extreme end of the claw underneath the head of the nail, assuming that the nail has been driven in to its fullest extent. After thus starting the extraction of the nail, it may be drawn out a little further by engagement of the parts 14^b and 15^b adjacent the end of the claw with the under side of the head, the hammer being

- rocked upon the surface 13^a (Fig. 1). In order to further extract the nail, it is necessary to either grip the shank of the nail or raise the surface upon which the part 13^a of the hammer is rocked, this latter expedient being ordinarily employed in the use of the usual well-known type of claw hammer as by placing a block underneath the head of the hammer.
- 10 By means of the claw shown in Figures 1-5, the shank of the nail may be securely gripped and the nail extracted in its entirety without the necessity of employing a block upon which to rest the hammer.
- 15 After the nail has been started, the now exposed shank is moved further into the converging space between the jaws 14 and 15 until the shank contacts the opposing faces of the parts 14^b and 15^b. When the hammer is now rocked upon the surface 13^a, the faces of the parts 14^b and 15^b are in frictional engagement with the shank of the nail, and as a lifting force is exerted by rocking the hammer the parts 14^b and 15^b tend to spring downwardly relative to the more rigid parts 14^a and 15^a, and as these parts spring downwardly they approach each other securely gripping and biting into the shank of the nail. The greater the force exerted in pulling the nail, the greater is this gripping action of the inner resilient portions of the jaws. When the nail has been extracted as far as possible with the first grip upon the shank as described, a new and lower grip and any successive required number of grips may be taken until the nail is entirely extracted.
- 20 Referring now to the modified form shown in Figure 6, the jaws forming the claw are in this instance made preferably in two parts. The outer or main portions 16 and 17 of the jaws are substantially rigid, as in the usual type of claw hammer. Inserted in these parts 16 and 17 are a pair of resilient strips 18 and 19 respectively, which project from the inner sides of the two jaws and form the nail engaging portions thereof. These strips 18 and 19 are curved upwardly, as shown, and their action will be understood to be substantially the same as that of the parts 14^b and 15^b of the embodiment shown in Figures 1-5. As a lifting force is exerted upon the shank of a nail between the opposing faces of the two strips 18 and 19, the strips tend to spring downwardly relatively to the rigid parts 16 and 17, and in so doing they move toward each other, gripping the nail more and more securely.
- 25 The embodiment shown in Figure 7 is similar to that shown in Figure 6, except that the resilient strip 18 is omitted. The shank of the nail is received between the inner edge of the upwardly curved strip 19 and the face 16^a of the rigid part 16. As a lifting force is exerted, the part 19 in frictional engagement with the shank of the nail swings downwardly and toward the jaw 16 so that the shank is securely gripped between the spring 19 and the surface 16^a.
- 30 In the embodiment shown in Figure 8, the two jaw portions 20 and 21 are substantially rigid and a pair of resilient strips 22 and 23 are fastened to the outer rounded surfaces thereof, as by means of securing devices 24. The inner edges 22^a and 23^a of the strips 22 and 23 curve upwardly between the two jaw members 20 and 21, and the shank of the nail is received between their opposing faces. In action, the parts 22^a and 23^a spring downwardly and inwardly toward each other relative to the rigid parts 20 and 21, securely gripping the shank of the nail.
- 35 Figure 9 shows a construction similar to that of Figure 8, the two spring strips 25 and 26 being secured to the two rigid jaw members 27 and 28 respectively by being inserted therein along their outer edges 25^a and 26^a. Their inner portions 25^b and 26^b curve upwardly between the rigid jaw members 27 and 28, and the shank of the nail is gripped between the opposing faces of these parts 25^b and 26^b, as will be understood from the above.
- 40 Referring now to Figure 10, there is shown a further modified form of this invention. The two jaws 29 and 30 of the claw are preferably substantially rigid. Adjacent their junction with the body 31 of the hammer, and on the side thereof toward the handle, the metal of the jaws is weakened as by grooves 32 and 33. These grooves are cut on diagonal lines, as shown, and when a lifting force is exerted on the nail through the jaws 29 and 30, the metal thereof gives slightly along these diagonal lines. The effect is that the two jaws 29 and 30, as the metal yields, spring downwardly and inwardly toward each other relative to the body 31. The opposing faces of the jaws 29 and 30 thus moving toward each other, move into tight gripping engagement with the shank of the nail, and the greater the pulling force exerted the tighter the gripping engagement becomes. The action is thus similar to that described with regard to Figures 1-5 and the nail may be completely withdrawn with the greatest convenience.
- 45 If found desirable in order to improve the gripping action of the construction just described in connection with Figures 10 and 11, a fine slot 34 may be cut in the body of the claw opposite and parallel with the grooves 32 and 33. Such a slot 34 materially increases the yielding action and hence the gripping action of the jaws without materially weakening the structure, since the force which the metal at this part is called upon to withstand is a force of compression.
- 50 In Figures 13 and 14 there is shown a construction in which the action is similar to that just described in connection with Figures 10-12. In this construction the jaws 35 and

90 70 75 80 85 90 95 100 105 110 115 120 125 130

16 17 18 19 20 21 22 23 24 25 26 27 28 29 30 31 32 33 34 35 36 37 38 39 40 41 42 43 44 45 46 47 48 49 50 51 52 53 54 55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

36 are of substantially rigid material, and are made separate from the body 37. The jaws 35 and 36 are pivoted to the body 37 by means of suitable lugs 38 and 39 and diagonal pivot pins 40 and 41 respectively. Resilient means such as a pair of spiral springs 42 and 43 normally hold the jaws in the position shown in Figure 14. The shank of the nail is received between the opposing faces of the two jaws 35 and 36, and when a lifting force is exerted the two jaws frictionally engaging the nail, swing downwardly about their pivots 40 and 41. In so swinging the two jaws approach each other and securely grip the shank 15 of the nail. When the grip is released, the springs immediately return the jaws to their original positions in readiness for taking a new grip.

From the foregoing, it will be seen that 20 there is herein provided apparatus which embodies the features of the invention and attains the objects thereof, including many important practical advantages. The structures described are simple and adapted to operate 25 in a highly efficient manner in the performance of the results to be achieved.

As many possible embodiments may be made of the above invention, and as many changes might be made in the embodiment 30 above set forth, it is to be understood that all matter hereinbefore set forth is to be interpreted as illustrative and not in a limiting sense.

I claim as my invention:

35 1. In construction for claw hammers and the like, a nail extracting claw having substantially rigid supporting parts and resilient nail engaging parts, said nail engaging parts being adapted upon nail extracting movement 40 of said claw to move downwardly and inwardly toward each other relative to said rigid parts and into gripping engagement with said nail.

2. In construction for claw hammers and 45 the like, a nail extracting claw comprising a pair of spaced jaws converging toward the body of the claw, the inner nail engaging portions of at least one of said jaws being of resilient material and normally directed upwardly toward the head of the nail being extracted.

3. In construction for claw hammers and 55 the like, a nail extracting claw comprising a pair of spaced jaws converging toward the body of the claw, the inner nail engaging portions of said jaws being of resilient material and normally curved upwardly toward the head of the nail being extracted, the amount of said upward curve increasing progressively from the end of the claw toward the body thereof.

4. In construction for claw hammers and 60 the like, a claw comprising a pair of curved jaws lying substantially in the same plane at their outer flattened ends and at least one

of which is adapted to move from its normal position toward the other upon a nail being gripped therebetween and the claw being swung in a nail-drawing direction.

5. In construction for claw hammers and 70 the like, a nail extracting claw comprising a pair of spaced jaws converging toward the body of the claw, said jaws being of resilient material and the inner nail engaging portions thereof being normally directed upwardly toward the head of the nail being extracted and the outer portions thereof being reinforced and substantially rigid.

6. A claw hammer having diverging nail-engaging portions and means mounting at 80 least one of said portions on the hammer and forming an axial connection therefor inclined with respect to the longitudinal center-line to the hammer head and of such resilience as to cause it to yield in use, in the direction of 85 the other nail-engaging portion.

7. A claw hammer having diverging nail-engaging portions and means mounting at 90 least one of said portions on the hammer and forming an axial connection therefor inclined with respect to the longitudinal center-line to the hammer head and of such resilience as to cause it to yield in use, in the direction of 95 the other nail-engaging portion, the axis of said axial connection being closer to the outer surface of the claw than is the gripping edge of the nail-engaging portion which swings about the same.

8. A claw hammer having curved nail-engaging portions diverging longitudinally of the hammer head and integral portions connecting at least one of the same with the body of the hammer head of a resilience which will cause said portion to yield in use, and shaped to form an axial connection which is non-perpendicular to the effective edge of the other nail-engaging portion.

9. A claw hammer having a pair of nail-engaging portions diverging longitudinally of the hammer head, at least one of which follows substantially throughout the length of the claw and is inclined away from the outer surface of the claw and is of a resistance to initial bending less than the bending stress in use thereon whereby it bends in use.

10. A claw hammer, the claw of which 110 comprises gripping portions formed of resilient material and inclined toward each other in a direction away from the bearing surface of the claw and having a resistance to initial bending less than the bending stress imposed thereon in use whereby it bends in use, and the outer portion of the claw being relatively rigid to reinforce said gripping portions.

11. A claw hammer having a pair of diverging curved nail-engaging portions and integral means mounting at least one of said nail-engaging portions upon the body of the head of the hammer and forming a resilient 120

axial connection of a resistance to initial bending less than the bending stress to which it is subjected in the use of the hammer, whereby it bends in use, and normally holding the nail-engaging portion mounted thereon in a position from which movement about the axis of said connection will move its engaging surface toward the engaging surface of the other nail-engaging portion.

12. A claw hammer having mounted upon at least one of its claws a resilient member provided with a gripping edge and an integral portion connecting it with the claw and shaped to tend to move said edge toward the other claw under the stress to which it is subjected to use, said connection having a resistance to initial bending less than the bending stress imposed thereon in use.

13. A claw hammer having mounted upon at least one of its claws a strip of resilient metal provided with a gripping edge and so connected with said claw as to move said edge toward the other claw in use, said member being shaped and of such resilience as to be distorted by the stress imposed by use.

In testimony whereof, I have signed my name to this specification this 23rd day of January, 1925.

ROBERT S. BLAIR.
